(57) **CLAIM**

I claim the ornamental design for a growler with lid, as shown and described.

DESCRIPTION

FIG. 1 is a perspective view of a growler with lid, showing my new design;

FIG. 2 is a front elevational view thereof;

FIG. 3 is a rear elevational view thereof;

FIG. 4 is a left-side elevational view thereof, the right-side elevational view being a mirror image thereof;

FIG. 5 is a top plan view thereof;

FIG. 6 is a bottom plan view thereof; and,

FIG. 7 is a cross-sectional view thereof, taken along line 7-7 of FIG. 2.
